EDWARD E. JOHNSON, OF ST. PAUL, MINNESOTA.

MEANS FOR FORMING METAL RIBBONS.

1,315,022.

Specification of Letters Patent.

Patented Sept. 2, 1919.

Application filed December 1, 1916. Serial No. 134,296.

To all whom it may concern:

Be it known that I, EDWARD E. JOHNSON, a citizen of the United States, residing at St. Paul, in the county of Ramsey and State of Minnesota, have invented certain new and useful Improvements in Means for Forming Metal Ribbons, of which the following is a specification.

My invention relates to means for forming metal ribbons used in making well screens and has for its object to provide mechanism for arranging a multiplicity of shaped elements which are wider at one portion than another, so that the narrowest portions will 10 be turned in one direction and the elements held parallel and spaced a desired amount between their widest portions, together with mechanism for applying solder to said elements at intervals, whereby a continuous 15 ribbon is formed which may be wound upon a perforated tube to construct a well screen. The elements are preferably formed of wire which is triangular in cross section and which is wound with one apex of the wire at 20 one outer limit of the resulting ribbon and a side of the wire in the other outer limit. The total number of wires needed to form the ribbon are passed in parallel relation between a roller and a holding block whereby 25 they are arranged and spaced. As so held, the ribbon thus formed is passed over a drum where a flux is applied at intervals along the ribbon, and upon another drum a soldering head is successively clamped over 30 the ribbon at the points where the flux was applied, and solder ejected about and over the wires to secure them in their fixed relation. The ribbon thus formed is then 35 scraped clean from excess of solder and wound upon a reel. Operations are automatically and continuously performed by 40 my machine so that an attendant is only needed to supply the raw material and remove the product.

45 The full objects and advantages of my invention will appear in connection with the detailed description thereof and are particularly pointed out in the claims.

50 In the drawings, illustrating the application of my invention in one form,—

Figure 1 is a plan view of my machine. Fig. 2 is a front elevational view of the same drawn to a slightly reduced scale. Fig. 3 is a plan sectional view taken on line 3—3 of 55 Fig. 2. Fig. 4 is an elevational sectional view taken on line 4—4 of Fig. 1. Fig. 5 is

an elevational sectional view similar to Fig. 4 taken on line 5—5 of Fig. 1 with certain parts cut away and left out to provide clearness. Fig. 6 is a fragmentary elevational 60 sectional view of the machine taken on line 6—6 of Fig. 3. Fig. 7 is a rear elevational view of the parts shown in Fig. 6. Fig. 8 is an elevational sectional view of the solder pot and ejector taken on line 8—8 of Fig. 1. Fig. 9 is an enlarged sectional elevational 65 view taken through the valve mechanism of the solder pot on line 9—9 of Fig. 1. Fig. 10 is a plan sectional view of the parts shown in Fig. 9 taken on line 10—10 of Fig. 70 9. Fig. 11 is an enlarged elevational view of a portion of the device shown in Fig. 5 and similar thereto, with some of the parts shown in section. Figs. 12 and 13 are plan 75 views of parts of the machine shown in Fig. 1 with some of the parts in altered relations to each other and other parts cut away to show those beneath. Fig. 14 is a fragmentary elevational view as seen from the right 80 of the machine, illustrating the counting mechanism. Fig. 15 is an enlarged central elevational sectional view of the clutch head operating the winding mechanism taken along one of the arms. Fig. 16 is a plan 85 sectional view of the parts shown in Fig. 15 taken on line 16—16 of Fig. 15. Fig. 17 is an enlarged elevational sectional view of a portion of the winding reel taken on line 17—17 of Fig. 1. Fig. 18 is an enlarged 90 elevational view of a portion of the soldering drum. Figs. 19 and 20 are elevational sectional views of the portion of the soldering drum shown in Fig. 18 taken on lines 19—19 and 20—20, respectively, of Fig. 18. Fig. 21 is a fragmental section taken on line 95 21—21 of Fig. 1. Fig. 22 is a cross sectional view of a piece of finished ribbon. Fig. 23 is a top plan section of the soldering head taken on lines 23—23 of Fig. 11.

In the construction of my well-screen ribbon I prefer to use triangular wire which when arranged and constructed as shown in Fig. 22 comprises the finished ribbon, which may be wound upon a perforated pipe to form a well screen capable of being driven. The various steps followed in constructing 100 this ribbon are most clearly shown in Fig. 1. Strands of the triangular wire 30 are fed into the machine between two drums 31 and 32, of which drum 32 is the driver and 105 drum 31 an idler. The drum 31 is provided with circumferential grooves 33, as best seen

in Fig. 21, into which the strands 30 are forced by a head 34 clamped tight up against the faces of the strands. As the wires 30 pass over drum 32 said wires have applied 5 to them at certain regular intervals a soldering flux contained in a tray 35 by means of a toothed roller 36 which engages a conical roller 37 partly immersed in the flux. Roller 36 and drum 32 are geared to revolve in a 10 ratio such that a tooth 38 on roller 36 shall always come opposite to a groove 39 on the periphery of drum 32, permitting the flux applied to wires 30 to flow freely about the same and be properly applied thereto without daubing drum 32. In leaving drum 32 the wires pass over a second drum 40, which is provided with circumferential grooves 41 similar to grooves 33 in drum 31, and is also provided with transverse pockets 42. Drum 20 40 is geared to rotate with drum 32 so that the spots on the wires which have been coated with flux always come opposite the pockets 42 in the drum 40. While the wires are passing about drum 40 a soldering head 25 43 communicating with a solder pot 44 is successively brought up against the drum 40 and clamped thereto by a toggle clamp 45 and solder ejected from the pot 44 through head 43 about the wires 30 into the pockets 30 42 provided for that purpose by means of a pump 46 extended down into said solder pot. A perfect soldering action cannot be effected unless the metal to which the solder is to 35 adhere is raised to the temperature of the solder. In my machine this is accomplished from the fact that solder not only is applied about the wires and in the pockets 42 by the pump 46, but an excess of this solder is passed over the wires discharging back into 40 the solder pot, this flow of solder continuing for a time sufficient to raise the wires or strand to proper soldering temperature. Head 43 is adapted to travel with drum 40 for a short period of time while solder is 45 being ejected about and over the joint and then is returned to its original position, being then ready to form the next joint. Before the ribbon leaves the drum 40 it is cleaned by being scraped with a knife 47. 50 The ribbon finally passes over an idler 48 and is coiled upon a reel 49, from which it may be easily removed in coils.

The frame of my novel machine, as best shown in Fig. 2, consists of a box-like structure substantially open at the front and rear, comprising side members 50 and 51 and top and bottom members 52 and 53. This structure is supported upon pairs of legs 54 and 55 attached to the frame member 36, which 60 legs may be bolted to the floor.

The driving mechanism for the machine is most clearly shown in Fig. 3. A motor 56 is bolted to a bracket 57 issuing from the frame members 50 and 53. Bracket 57 is provided 65 with an upright portion 58 to which is se-

cured a long bearing 59 supporting the motor shaft 60. The aperture 61 in portion 58 of bracket 57, through which bearing 59 extends, is of ample size so that the motor shaft 60 and a worm gear 62 secured to the end 70 thereof may be passed through said aperture, thus facilitating the assembling of the machine. Worm gear 62 meshes with a worm wheel 63 loose on a shaft 64 journaled at one end in a boss 65 integral with the frame member 51 and at the other end in a boss 66 formed on a plate 67 bolted to the frame member 50. Plate 67 covers an aperture 68 in the frame member 50 through which the shaft 64, with all its parts, may pass in assembling the machine. Worm wheel 63 is provided with a clutch member 69 engaging a corresponding clutch member 70 splined to shaft 64, which latter clutch member may be operated from the front of the machine by a lever 71 pivoted to an arm 72 issuing from frame member 50 and terminating in a forked portion 73 operating in a groove 74 in said clutch member. Shaft 64 may hence be considered as the drive shaft of the 90 machine.

The method of attaching the drum 31 to the machine and details of the arranging head 34 will be found in Fig. 21. A studded screw having an enlarged central portion 75 is threaded at both ends 76 and 77 and is attached to the frame member 52 by the end 77 which is screwed therein. Journaled upon the enlarged portion 75 of this stud is the idler drum 32 which is retained thereon by a washer 79 and a nut 78 screwed on the end 76 of said stud. The head 34 of the arranging and spacing member is slidably mounted in a socketed casting 80 attached to the frame member 52 through a base plate 81. Head 34, as noted in Fig. 21, is provided with a stem portion 82 which slides in the socket 83 in casting 80 and can be advanced up against strands 30 with any desired pressure by means of a screw 84 which is threaded into casting 80 and butts up against the end of stem 82.

The flux applying device is best shown in Figs. 1 and 4. Drum 32 is attached to a reduced portion 85 of a shaft 86 journaled in bosses 87 and 88 integral with frame members 52 and 53 by a washer 90 and a nut 91. Roller 36 is similarly secured to the reduced end 89 of a shaft 92 journaled in bosses 93 and 94 integral with the frame members 52 and 53 by means of a similar washer 95 and nut 96. Shafts 86 and 92 are geared together by gears 96 and 97 fast thereon, and are driven by a drive to be later explained. The teeth 38 on the roller 36, as best seen 125 in Fig. 1, have inserted in them strips of felt or cotton 98 which run the length thereof and which receive flux from the cone roller 37 and apply it to the strands on the drum 31. The tray 35 extends under drum 130

31 so that all of the flux which drops off from the strands 30 returns to the tray. Tray 35 also extends out beyond the rear of the frame member 52, where a corked 5 draining spout 97 is provided. The cone roller 37 is preferably made of felt the more easily to retain and carry the flux, and has a stem 98 attached to it which rotates in a bearing 99 integral with a bracket 100 se- 10 cured to the bottom of the tray 35. The apex of cone roller 37 is ninety degrees, so that the lower portion of the cone travels in the flux parallel to the tray 35 and the forward portion of the same travels parallel to 15 the flux applying roller 36. Roller 36 fits tight enough up against roller 37 so that the latter is rotated a small amount every time one of the teeth 38 engages it. In this manner the flux is brought up from the tray 35 20 to the spaced wires 30. To prevent flux from entering the bearing 93 of shaft 92, a boss 115 integral with tray 35 is provided which surrounds a portion of shaft 92 and roller 36 and extends up even with the top of 25 said tray.

The soldering drum 40 and the drive for it, as well as the drive for the drum 32 and roller 36, are shown in Figs. 3, 5 and 11. Referring to Fig. 11, drum 40 is bolted to an 30 escapement wheel 101 which in turn is secured by a key 102 to a hollow shaft 103 journaled in bosses 104 and 105 integral with the frame members 52 and 53, as seen in Fig. 5. Shaft 103 has secured to it adjacent the hub 105 a spur gear 106 which meshes with the gear 96 on shaft 86 and a bevel gear 107 meshing with a bevel pinion 108 below it, as seen in Fig. 3, attached to a short shaft 109 journaled in a boss 110 integral with the frame member 51. Shaft 109 extends out beyond frame member 51 at 112, where it has attached to it a spur gear 111 meshing with a spur gear 113 secured to a similar portion 114 of the 40 drive shaft 64. Gears 96, 97, and 106 are so proportioned that as the same rotate the slots on the drum 32 and pockets in drum 40 always come opposite the places on the wires 30 coated with flux by the roller 36. The ratio of gears between shaft 64 and shaft 103 is such that when shaft 103 has rotated through an angle equal to that between two of the pockets 42 on drum 40 then shaft 64 shall have completed one revolution. All of the operations pertaining to 50 each joint in the ribbon can hence be referred to a single revolution of shafts 64, and will be so discussed.

In forming the soldered joints, as before 60 stated the soldering head 43 is first clamped against the drum 40, then follows it for a period of time while solder is being forced about and over the wires 30 at the joint, and is finally released and returned to its 65 original position to engage the wires 30 at

the new joint to be formed. The device for successively performing these functions is clearly shown in Figs. 1, 5, 11, 12 and 13. Rotatable on shaft 103 and shouldered against a portion 116 of disk 101, which 70 protrudes through the drum 40, is a casting 117 supporting the soldering head 43. Casting 117 and disk 101 are secured from longitudinal motion on shaft 103 by a collar 118 integral with said shaft and resting upon 75 the frame member 52 and by a nut 119 tapped to screw upon the end of said shaft against a shoulder 120. Casting 117 has radially-extending portions 121 and 122 of which portion 121 supports a vertically 80 swinging arm 123 pivoted thereto at 124. The lower portion 125 of arm 123 has secured to it the soldering head 43, which will later be explained in detail, and the upper portion 126 of said arm is forked and has 85 pivoted to it at 127 a member 128 of a system of toggle levers, the other member 129 of which is pivoted at 130 to a forked lug 131 issuing from the radial portion 122 of casting 117. It will be noted that member 90 128 of the toggle levers is forked at 132, where it has pivoted to it at 133 the other member 129 of said toggle levers. The toggle is operated by a forked head 134 through which the same pivot 133 extends, which head is securely attached to the end of a rod 135 freely positioned within the hollow shaft 103. The lower end of rod 135, as best seen in Fig. 5, is securely bolted to one member 136 of an end thrust 100 ball bearing, the other member 137 of which is clamped to a sleeve 138 surrounding the rod 135. Sleeve 138 is threaded to receive a channeled collar 139 which can be vertically adjusted 105 within the same and by which the whole rod 135 is elevated and lowered through a cam lever 140. Lever 140 is pivoted at 141 to a casting 142 secured to the underside of the frame member 53 and terminates in a hooked 110 portion 143 surrounding the drive shaft 64, which portion has secured to it cam rollers 144 and 145, respectively, engaging cams 146 and 147 attached to shaft 64. Cam 146, as clearly shown in Fig. 5, is lowest at 148, 115 rises gradually at 149, is uniformly highest at 150 for the greater part of the circumference of the same, and drops quickly at 151 to the elevation at 148. Cam 147, which is simply a follower and is complementary 120 to cam 146, serves to positively actuate lever arm 140. As shaft 64 rotates in the direction shown by the arrow, the portion 149 of cam 146 engages roller 144, causes lever 140 to be oscillated downward and 125 clamps the head 43 against drum 40. The head 43 remains clamped for the greater part of the revolution of shaft 64, while the roller 144 rides upon the cam surface 150 and quickly disengages when said roller 130

engages surface 151, remaining released a short time while at 148. This effectually clamps head 43 against drum 40 and permits it to remain in contact while solder is flowing for the greater part of the revolution of shaft 64 and quickly releases the same at the proper time.

The mechanism for oscillating and accurately timing the clamping head and toggle arrangement is shown in Figs. 1, 3, 5, 6, 7, 11, 12 and 13. As best shown in Figs. 1 and 5, the radial portion 122 of casting 117 extends downward at 151', where it is grooved at 152 to receive a vertically-positioned pin 153 having a tongued head 154 adjustably held in said groove by a bolt 155. Pin 153 is engaged by a slotted arm 156 keyed to a vertically-positioned shaft 157 and is adapted to operate in a slot 158 in said arm. Shaft 157 is journaled in bearings 159 and 160 cast with the frame members 52 and 53 and is adapted to oscillate to move the toggle head back from one joint to the next. Attached to shaft 157, as seen in Figs. 6 and 7, is a casting 161 to which is secured a diagonally-positioned flat spring 162. Spring 162 carries at its extreme end a forked bearing 163 in which is pivoted a spherical-surfaced cam roller 164 engaging a cam 165 fast upon the drive shaft 64. As best seen in Figs. 12 and 13, arm 156 is provided with a detent 166 which is adapted to engage, as hereinafter described, a number of teeth 167, 168, etc., on the disk 101 which equal in number and rotate in fixed relation to the die pockets 42 of drum 40. When the cam 165 is positioned as shown in Fig. 6, arm 156 and the toggle head are positioned as shown in Fig. 13, with detent 166 free from and out of the path of the teeth 167, 168, etc. As shaft 64 rotates, roller 164 engages the cam surface 169, and arm 156 and the toggle head are shifted approximately to the positions shown in Fig. 12 through the medium of pin 153 and slotted arm 156, with the detent 166 in the path of the oncoming tooth 168. At this instant roller 164 should be at the highest point 170 of cam 165. After the arm 156 arrives at the position shown in Fig. 12 the detent 166 is picked up by the advancing tooth 168, reversing the motion of lever 156, and through pin 153, the motion of head 117, which is still free to rotate independently of drum 40, as the toggle is open. The casting 117, carrying soldering head 43, is therefore timed accurately and caused to move forward with drum 40 through engagement of detent 166 and tooth 168, lever 156 having ceased to receive motion from cam 165 and the toggle still being open. The soldering head 43 is now clamped to the drum 40 by the toggle device previously described. The casting 117 now rotates

with drum 40, driving lever 156 in its backward stroke through the means of pin 153 and slotted arm 156, the relation of the parts being such that the detent 166 ceases to contact with tooth 168 and moves rapidly out of its path, where it remains until the revolution of shaft 64 again brings cam surface 169 into play. The cam surface 171 of cam 165 is negative only and might be left out as the retraction of lever 156, and through it lever 162, is secured from the toggle-head as described.

The adjustment afforded by groove 152 in head 117 and tongued head 154 of pin 153 serves to secure the accurate alinement of solder head 43 and die pockets 42 acting through detent 166 and tooth 167 and 168 as described. The casting 117 and solder head 43 continue to rotate with drum 40 until the operation of making a solder joint has been completed, when the toggle is opened by cam surface 149 and lever 140 and they are free to be returned to the position of Fig. 12, as described.

During the period of time when head 43 is clamped against drum 40 solder is being discharged through said head by a device shown in Figs. 8, 9 and 10. A tube 172 is supported in a socketed bracket 173 attached to a portion 174 of the frame issuing from the frame members 50 and 53 and by a casting 175 attached to a portion 176 issuing from the frame members 50 and 52, said casting having a fluted head 177 extending down into said tube. About the upper portion of tube 172 and spaced therefrom is a casting 178 secured to said tube by set-screws 179 and having cast therewith a circular frame portion 180 supporting the melting pot 44. Frame portion 180 has secured to it a jacket 182 having a vent pipe 183 leading from it to the rear of the machine, as shown in Fig. 5. Pot 44 is heated by means of a Bunsen gas burner 184 of usual construction supported from a bracket 185 attached to tube 172. The function of the tube 172 and the fluted connection 177 is to serve as an insulator to prevent heat from traveling to the major portion of the machine and greatly raise the temperature of the same. Attached to casting 178 and frame 180 by means of a bracket 186 is a pump 46 having a cylinder 187, shown in detail in Figs. 9 and 10. The cylinder chamber 188 communicates through ports 189 and 190 with a pair of valve chambers 191 and 192 provided in a casing 193 issuing from the bottom of the cylinder 187. Chambers 191 and 192 are closed at the tops by caps 194 and 195 having valve seats 196 and 197 therein engaged by balls 198 and 199, which balls are limited in motion by pins 200 and 201 passing diametrically through the chambers 191 and 192. Casing 193 forms a third chamber 202 which is socketed to receive the spherical end 204 of a

tube 203, which end is held in place for universal movement relative to said casing by means of a socketed plate 205 screwed thereon. A leakage port 206 is provided which leads to chamber 188 and which may be partially or completely closed by a screw 207 extending up above the melting pot 44. Cylinder 187 is provided with a piston 208 which is operated by means to be presently described. When the pot 44 is filled with solder the balls 198 and 199 float and are normally seated against the seats 196 and 197. As the piston 208 is raised, solder is drawn through valves 195 and 194 and also back through the tube 203 to fill the cylinder chamber 188. Upon the reversal of the movement of piston 208 the balls 198 and 199 again seat themselves and solder is forced up through the tube 203 and into the soldering head 43 with which said tube communicates. The quantity of solder discharged through head 43 is regulated by the leakage port 206 and valve 207, so that the excess amount is discharged out of cylinder chamber 188 through said port.

The means for operating the solder discharge pump 44 is shown in Figs. 4 and 8. Piston 208 is connected to a piston rod 209 by a ball-and-socket joint 210. A bridge 211 connects piston rod 209 with a rod 212 parallel thereto and slidably mounted in the head 177 and the bracket 173. Rod 212 is securely fastened in bridge 211, but rod 209 is secured therein for both longitudinal and lateral adjustment by means of a pair of nuts 213 and 214 advanceable upon the end 216 of rod 209 and passing through a slot 215 in said bridge. As seen in Fig. 4, rod 212 passes through bracket 173 and is provided at its lower end with a forked head 217 to which it is loosely pivoted at 218 one arm 219 of a bell-crank 220. Bell-crank 220 is pivoted in a casting 221 bolted to the underside of the frame member 53, and the other arm 222 of said bell-crank extends up through an aperture 223 in said frame member and carries a cam roller 224 which engages a cam 225 fast on shaft 64. Cam 225 is made with a gradually-sloping surface 226 which operates the pump uniformly to cause the same to deliver solder into the soldering head 43 while the latter is clamped to the drum 40. Cam roller 224 is kept in engagement with cam 225 by means of a tension coil spring 229 secured to arm 222 and to the bracket 57 of the frame proper. As the roller 224 is caused to follow surface 228 of cam 225 by means of spring 229 to pass from the position shown in dotted lines in Fig. 4, to the full line position, solder is drawn into the pump ready for another discharge. This latter action durates while the head 43 is being unlocked, returned and locked relatively to drum 40.

The soldering head and the connections 65 between the same and the pump are shown

in detail in Figs. 11 and 23. Head 43 is made of a cylindrical bar and has a longitudinal hole 230 partly through it which is eccentrically displaced relative to the axis of the bar. Hole 230 is plugged at the top 70 at 231 and turns at 232 to leave the bottom of the head 43 at the center of the head. The lower portion 233 of head 43 is threaded and socketed and receives a cap 234 which is also socketed, said sockets serving to hold the cylindrical head 235 of a tube 236 for universal movement relative to said head. Tube 203, leading from the pump 44, is arranged to telescope into tube 236, as shown in Fig. 8, so that the head 43 may have a 80 freedom to move with the drum 40 as previously prescribed and still communicate with said pump. Head 43 is slotted at 237 to form a longitudinal passageway from hole 230 to the exterior of the head. The 85 head is set in a socket 238 formed in the arm 123 and is securely clamped in place by a bar 239 inserted in a recess 240 in said head and secured to the arm 123 by bolts 241. The passageway 237 in head 43 communicates through another passageway 242 in arm 123 with a chamber 242^a, and said chamber terminates in a narrow nozzle formed by two blocks 244 and 245 of stellite or other substance to which melted solder 95 does not adhere, and through which the fluid metal is squirted against the wires 30. These blocks are clamped in place upon the arm 123 by plates 246 and 247 screwed thereto and are furnished with sharp-edged lips *a* 100 and *b* which come in direct contact with the wires 30 upon drum 40. The lower end of chamber 242 is left open so that the solder can return freely through it to the melting pot below.

The action, which is not a casting process but a true soldering process is as follows. The arm 123 with solder head 43 being clamped tight against the wires 30, lying in the drum 40 and opposite a die pocket 110 42, the flux also covering the wires 30 at that point, the molten solder is forced through slot 237 in a jet against and between the wires, raising them quickly to soldering temperature, the stream of slightly-cooled 115 solder falling into the solder pot. This action is continued for a definitely-timed period during which the stream of molten solder is flowing over the wires and discharging into the solder pot, so that the wires are 120 certainly raised to the necessary temperature to effect a perfect soldering action.

The grooves 41 in drum 40 are cleaned from solder which may stick in them by a scraper 320 adjustably positioned in an upright 125 321 attached to the frame member 52. Knife 47, which cleans the ribbon, is mounted on a bracket 322, which may also be adjusted a small amount.

The winding reel is best shown in Figs. 130

1, 2, 15, 16 and 17. A large wheel 248 on which the ribbon is wound, having the upper surfaces of the spokes 249 level with the top of the rim 250 and level with the 5 bottom of the finished ribbon as it leaves the drum 40, is pinned to a shaft 251 journaled in a long tubular bearing 252 cast integral with a bracket 253 bolted to the frame member 50. As best seen in Figs. 1 and 10 17, the upper portion 254 of shaft 251 is reduced in diameter and is threaded to receive and retain upon wheel 248 a collapsible winding core. This core comprises four segments 255, 256, 257 and 258, which when 15 arranged together and properly spaced, as shown in Fig. 1, present a sectional disk having an annular groove 259 and a conical bore 260. Groove 259 is adapted to receive a flanged annular ring 261, and the bore 260 is arranged to receive a truncated conical plug 262 provided with keys 263 engaging corresponding keyways 264 in the various segments 255, 256, 257 and 258. Plug 262 is bored to receive the end 254 of shaft 251 and serves to wedge the said segments against ring 261 when a nut 265 on shaft end 254 is screwed down upon it. By this means the core formed is rigidly held together upon the center of wheel 248. In 25 attaching the ribbon to the core the ribbon is bent and the bend inserted in one of the spaces between the segments. In removing the core, nut 265 is unscrewed and the whole coil and core lifted up from the wheel 248. 30 When the coil has been properly bound together the cone 262 is knocked out from the back, loosening the core members and permitting removal of the same.

Shaft 251 is driven as shown in Figs. 2, 40 15 and 16. The lower end 266 of shaft 251 is reduced to form a shoulder 267 against which is seated a flanged casting 268 held in position by a nut 269 screwed on the end thereof. The flange 270 of casting 268 is recessed at 271 to receive a fiber washer 272. Upon casting 268 is rotatably mounted a 45 sleeve 273 which rests upon washer 272 and which is itself recessed at 274 to receive a similar fiber washer 275. The sleeve 273 is held in place upon casting 268 by a washer 276 and a nut 277 screwable upon the upper portion of casting 268. A friction drive is hence securable through the fiber washers 275 and 272 between sleeve 273 and the casting 268. Sleeve 273 serves as one member of a plurality of overrunning clutches of which a plurality of annular rings 278, 279 and 280 form the other members. These members are rotatably mounted upon the 50 sleeve 273 and are held in position upon this sleeve by means of the flange 270 and a flange 281 integral with said sleeve. Each of members 278, 279 and 280 is provided with drilled channels 282 which run into the 55 bore of said members and each channel is pro-

vided with a ball 283 held by a compression spring 284 seated against a pin 285 in contact with the periphery of the sleeve 273. Said clutch members are further provided with radially-extending arms 286, 287 and 288, which are screwed thereto as shown in Fig. 16. When these arms are successively oscillated wheel 248 is given a substantially uniform rotation.

Arms 286, 287 and 288 are indirectly operated from shaft 64. As shown in Fig. 2 a miter gear 289 is attached to the end of shaft 64 protruding beyond bearing plate 67, which gear meshes with a miter gear 290 attached to a shaft 291 journaled in a bearing 292 rigidly secured to said plate 67. The lower portion of shaft 291 has attached to it three eccentrics 293, 294 and 295, whose eccentric rods 181, 296 and 297 are provided with pairs of pins 298 and 299 which engage 85 the arms 286, 287 and 288, respectively, and cause the wheel 248 to be rotated.

It will be comprehended that as the coil of ribbon 300 upon the wheel 248 increases in diameter, the wheel 248 will have to be 90 proportionately rotated at a slower rate. To effect this I shift the position of the point of engagement of the eccentric rods with the arms 286, 287 and 288 in proportion to the diameter of the coil 300 as follows. Journaled in a bearing 301 integral with the bracket 253 is a shaft 302 to the upper end of which is attached an arched arm 303 having a roller 304 mounted at the end thereof and engaging the periphery of the coil of 100 ribbon 300. The lower end of shaft 302 has attached to it a downwardly-sloping arm 305 which terminates in a fork 306 embracing all of the eccentric rods. Fork 306 is practically under roller 304, and shaft 302 is 105 substantially in alignment with shaft 291. Roller 304 is kept in engagement with coil 300 by a spring 325 secured to arm 305 and the frame proper. As the coil 300 increases in diameter arm 303 is swung outward and 110 the arm 305 is correspondingly caused to shift the eccentric rods and increase the length of the lever arms 286, 287, and 288 to cause wheel 248 to rotate at the proper speed to wind the ribbon. The friction drive between the clutch member 273 and the shaft 251 provides for any irregularities in the action of the winding device should the same cause the wheel to rotate too great an amount.

In Fig. 14 is shown a counting device by 120 which the length of the ribbon in coil 300 may be determined. A counter 307 of ordinary construction, having actuating arms 308 and 309, is connected by means of these arms to a connecting link 310 eccentrically 125 pivoted to a gear 311. Gear 311 is the last of a train of reducing gears 312 driven from the pinion 113, and the train is so proportioned that the counter 307 records in feet.

In constructing ribbon of different sizes or 130

shapes of wire, or having different spaces between the wires, the drums 31, 32, 36 and 40 have to be removed and new ones replaced which satisfy the conditions of the ribbon. 5 For this reason drums 31, 32 and roller 36 have their operating shafts attached by nuts, so that the same may be adjusted to cause the slots thereon to take the correct positions relatively to those on the drum 40. It will 10 be noted in Fig. 11 that the whole toggle head may be lifted off from the machine by removing pin 133 and unscrewing nut 119. Drum 40 can then be removed and another placed upon the disk 101. Drum 40 can only 15 be placed upon disk 101 in one position, which is determined by the relations of the soldering head and the device for causing the same to stop at the correct position for each oscillation of said head. The adjustment for positioning of slots and the flux-applying device is hence procured by adjusting the other drums.

I claim:

1. A machine for securing together a 25 multiplicity of separate elongated elements of triangular cross section in spaced parallel relation, comprising means for feeding a multiplicity of said elements, means for holding and guiding said elements in spaced 30 parallel relation with a side and an apex of each element respectively in common planes, and means for applying solder to said elements in such position at intervals along the length of the same to form a continuous 35 ribbon.

2. A machine for securing together a multiplicity of separate elongated elements in spaced parallel relation, comprising means for feeding a multiplicity of said elements, means for guiding and holding the elements in spaced parallel relation, and means for applying solder across said held elements at regular intervals to form the same into a continuous ribbon.

3. A machine for securing together a multiplicity of separate elongated elements in spaced parallel relation, comprising means for feeding a multiplicity of said elements, means for guiding and holding 50 the elements in spaced parallel relation, means for applying solder transversely across said held elements at regular intervals to form the same into a continuous ribbon, means for removing excess of solder 55 from the ribbon, and means for winding the formed ribbon into a roll.

4. A machine for securing together a multiplicity of separate elongated elements in spaced parallel relation, comprising 60 means for feeding a multiplicity of said elements, means for guiding and holding the elements in spaced parallel relation, means for applying a flux transversely at fixed intervals across said held elements, 65 and means thereafter for applying solder

to the fluxed portions to form the elements into a continuous ribbon.

5. A machine for securing together a multiplicity of separate elongated elements of triangular cross section in spaced parallel relation, comprising means for feeding a multiplicity of said elements including a drum formed with V-shaped grooves for holding and guiding said elements in spaced parallel relation, and means for securing 70 said elements in such spaced and parallel relation while the same are guided and held by the drum.

6. A machine for securing together a multiplicity of separate elongated elements 80 of triangular cross section in spaced parallel relation, comprising means for feeding a multiplicity of said elements including a drum formed with V-shaped grooves for holding and guiding said elements in spaced 85 parallel relation, said drum having transverse grooves at fixed intervals about the periphery thereof, and means for applying solder to the elements at each of said grooves for securing said elements in position as held and guided to form the same 90 into a continuous ribbon.

7. A machine for securing together a multiplicity of separate elongated elements of triangular cross section in spaced parallel relation, comprising means for feeding a multiplicity of said elements including a drum formed with V-shaped grooves for holding and guiding said elements in spaced 95 parallel relation, said drum having transverse grooves at fixed intervals about the periphery thereof, a soldering head, means for successively clamping said soldering head upon the drum over said transverse grooves, a soldering pot, and means for 100 forcing solder from said pot into said transverse groove while the soldering head is clamped.

8. A machine for making metal screen ribbon out of separated elements, comprising means for feeding a multiplicity of said elements including a constantly-moving member engaging said elements and holding them in spaced parallel relation, a soldering head, means for successively clamping said 110 soldering head to said member and holding it clamped during a portion of the movement thereof, and means for applying solder through said soldering head while the same is clamped.

9. A machine for making metal screen ribbon out of separated elements of triangular cross section, comprising means for feeding a multiplicity of said elements including a constantly-movable member 115 formed with V-shaped grooves for holding and guiding said elements in spaced parallel relation as fed, a soldering head, means for successively clamping said soldering head to said grooved members transversely of 120 125 130

the grooves thereof and holding the head clamped during a portion of said movement, and means for applying solder to the parallel elements through the head while the same is clamped.

10. A machine for making metal screen ribbon out of separated elements of triangular cross section, comprising means for feeding a multiplicity of said elements including a continuously-moving member formed with V-shaped grooves for holding and guiding said elements in spaced parallel relation, said member having transverse grooves at fixed intervals along the same, a soldering head, means for successively clamping said soldering head upon said member over said transverse grooves and for holding the head clamped during a portion of said movement, and means for applying solder about said elements in the transverse grooves while the soldering head is clamped.

11. A machine for making metal screen ribbon out of separated elements of triangular cross section, comprising a rotating drum formed with V-shaped grooves for holding and guiding said elements in spaced parallel relation, a soldering head, means for successively clamping said soldering head upon the drum to move therewith and with said parallel elements for a limited time, and means for applying solder transversely to said parallel elements through said soldering head while the same is clamped.

- 35 12. A machine for securing together a multiplicity of separate elongated elements of triangular cross section in spaced parallel relation, comprising means for feeding and guiding said elements including a continuously-rotating drum formed of V-shaped grooves and a coöperating member for forcing an angle of said elements into said grooves and holding them positioned with a set of faces in a common plane, and means for successively securing the members in such position at intervals along the length of the same.

13. A machine for securing together a multiplicity of separate elongated elements of triangular cross section in spaced parallel relation, comprising means for guiding and continuously feeding said elements, a soldering head, means for successively clamping said soldering head transversely across said elements as held and fed, and means for applying solder to the elements while the soldering head is clamped.

14. A machine for securing together a multiplicity of separate elongated elements of triangular cross section in spaced parallel relation, comprising means for guiding and continuously feeding said elements, a soldering head, means for successively clamping said soldering head transversely across said elements as held and fed, a soldering pot

containing melted solder, and means for forcing solder from said pot and through said soldering head upon the held elements while the soldering head is clamped.

15. A machine for securing together a multiplicity of separate elongated elements of triangular cross section in spaced parallel relation, comprising means for guiding and continuously feeding said elements, a soldering head, means for successively clamping 75 said soldering head transversely across said elements as held and fed, a soldering pot containing melted solder, a pump operative in said soldering pot upon said melted solder and connections therefrom to the soldering 80 head, and means for operating the pump to force melted solder to the soldering head during the periods when the same is clamped.

16. A machine for securing together a multiplicity of separate elongated elements 85 in spaced parallel relation, comprising means for guiding and holding the elements, means for continuously feeding the elements, and means for applying solder across said held elements at regular intervals while the 90 elements are being fed.

17. A machine for securing together a multiplicity of separate elongated elements in spaced parallel relation, comprising 95 means for guiding and holding the elements, means for continuously feeding the elements, and means for securing said elements at separated points transversely of the same while the elements are held and fed.

18. A machine for securing together a 100 multiplicity of separate elongated elements in spaced parallel relation, comprising means for guiding and holding the elements, means for continuously feeding the elements, a soldering head, a soldering pot containing melted solder, means for successively clamping said soldering head to and across the group of elements and for releasing the same as the same are being fed, and means for forcing melted solder from the pot to 105 the soldering head and across the group of elements for securing the same at separated points along the length thereof.

19. A machine for securing together a multiplicity of separate elongated elements 115 in spaced parallel relation, comprising means for guiding and holding the elements, means for continuously feeding the elements, and means for soldering said elements at the separated points in narrow transverse 120 lines across all of the elements while the elements are held and fed.

20. A machine for soldering together a plurality of elongated elements at separated points along the length thereof, comprising 125 means for continuously feeding the elements, a soldering head, means for holding the soldering head transversely upon the elements as the same are fed, and means for ejecting solder upon and around the ele- 130

ments through said soldering head while the same is held.

21. A machine for soldering together a plurality of elongated elements at separated 5 points along the length thereof, comprising means for continuously feeding the elements, a soldering pot containing molten solder, a soldering head having a connecting conduit extending into said molten solder, means for holding the soldering head upon the elements for successive fixed intervals while the elements are fed, and means for injecting solder through said conduit and head transversely upon the elements while 10 the head is held.

22. A machine for soldering together a plurality of elongated elements at separated points along the length thereof, comprising means for continuously feeding the elements, 20 a soldering pot containing molten solder, a soldering head having a connecting conduit extending into said molten solder, means for holding the soldering head upon the

elements for successive fixed intervals while the elements are fed, a pump operative upon 25 said molten solder to force the same through said conduit and soldering head, and means for operating the pump timed to inject solder while the soldering head is held.

23. A machine for soldering together a plurality of elongated elements at separated 30 points along the length thereof, comprising means for continuously feeding the elements, a soldering pot containing molten solder, a soldering head having a connecting conduit 35 extending into said molten solder, means for holding the soldering head upon the elements for successive fixed intervals while the elements are fed, a pump extending into 40 said molten solder and having pivotal connection with said conduit, and means for operating the pump timed to inject solder while the soldering head is held.

In testimony whereof I affix my signature.

EDWARD E. JOHNSON.
